CLAIM

The ornamental design for a shoe upper, as shown and
described.

DESCRIPTION

FIG. 1 is left side elevational view of a shoe upper
showing our new design;

FIG. 2 is a right side elevational view thereof;

FIG. 3 is a top plan view thereof;

FIG. 4 is a front elevational view thereof; and,

FIG. 5 is a rear elevational view thereof.

The broken line showing of a shoe sole in the figures is
environmental only and forms no part of the claimed
design.*FIG. 1*

FIG. 2

FIG. 3

FIG. 4

FIG. 5
